UNITED STATES PATENT OFFICE.

JOSEPH N. DUMAS, OF OXFORD, MASSACHUSETTS, ASSIGNOR TO CROMPTON & KNOWLES LOOM WORKS, OF WORCESTER, MASSACHUSETTS, A CORPORATION OF MASSACHUSETTS.

ELECTRICAL MULTIPLIER FOR LOOM BOX MOTION.

Application filed August 4, 1927. Serial No. 210,668.

This invention relates to improvements in multipliers for the box motions of looms and it is the general object of the invention to provide an electrically controlled mechanism wherein any selected shuttle may be kept in action for any desired length of time.

Many patterns or repeats call for the occasional use of one shuttle and the rather frequent use of other shuttles and a pattern chain to control such a sequence and made in the usual way would be of considerable length because of the fact that a great number of picks might lie between those picks laid by the shuttle which is only in occasional use. Numerous mechanical devices have been employed for shortening the length of the box chain, said motions usually employing an auxiliary or counter chain which turns while the main chain is at rest to hold any selected shuttle in action for a number of successive picks. These mechanical devices are so constructed that the different pattern and multiplying chains can get out of step with each other unless the weaver is careful in making a pick-out and it is an important object of my present invention to provide a motion for counting a large number of successive picks wherein chains and the like will be omitted and wherein the surfaces which determine the sequence in which the shuttles shall be active will be stationary and not subject to relative movement.

It is a more particular object of my invention to arrange the controlling contacts in two parallel groups so that the contacting member may move the length of one group while weaving half the pattern and then have a reverse movement to render operative the other set or group of contacts to complete the pattern, thereby leaving the contacting member in the same position at the start of each repeat to be woven.

It is a still further object of my invention to combine a cam box motion with a pair of intermediate devices one of which oscillates at all times with the cam box motion while the other device is connected to the first device or disconnected from it depending upon whether the boxes are to be controlled by the cam box motion or by the multiplying mechanism.

With these and other objects in view which will appear as the description pro-

ceeds, my invention resides in the combination and arrangement of parts hereinafter described and set forth in the claims.

In the accompanying drawings wherein I have shown my invention as applied to a loom having two drop boxes,

Fig. 1 is a side elevation of a loom showing my invention applied thereto, the electric circuits being indicated diagrammatically, with the parts in such a position that the cam box motion controls the boxes,

Fig. 2 is an enlarged side elevation of the disk members or devices by means of which the boxes are moved,

Fig. 3 is a front elevation taken in the direction of arrow 3, Fig. 2,

Fig. 4 is an enlarged detail side elevation of the actuating portion of the multiplier, parts being in section,

Fig. 5 is a horizontal section on line 5—5, Fig. 4,

Fig. 6 is an enlarged horizontal section on line 6—6 of Fig. 1, showing the sliding contact member and the method of mounting the same, and

Fig. 7 is a detail view showing the switch controlling the contacts which determine the movements of the boxes.

Referring particularly to Fig. 1 it will be seen that I have provided a loom frame 10 in which is mounted a crank shaft 11 and a lay 12 provided with a pair of shifting drop boxes 13 supported on a box rod 14. The rod 14 extends through a sleeve 15 guided by rocker foot 16 mounted on rocker pin 17 and said sleeve has connection with the lower end of a box lifting chain 18 extending upwardly over sheave 19 and down around a lower sheave 20 loose on the rocker pin. A spring S surrounds rod 14 and lies between the sleeve and the boxes 13 to communicate lifting movement of the chain to the boxes. A collar C on the rod 14 limits the spring and boxes. The box motion may be substantially the same as that shown in prior Patent No. 329,396 issued October 27, 1885 to L. J. Knowles. While I have shown a particular form of box motion yet I do not wish to be limited to the same.

In the lower part of the loom frame there is mounted a cam shaft 21 making a complete revolution in four picks and having secured thereto a box cam 22. Said cam has high and low dwell portions 23 and 24,

respectively, with intermediate lifter surfaces 25 all of said surfaces cooperating with a box lifting cam lever 26 pivoted as at 27 to the fixed part of the frame. The particular 5 form of box cam and lever may be varied and I do not wish to be limited to the particular form as set forth herein.

My invention relates to the mechanism for controlling the boxes 13 so that they 10 may either be lifted and depressed as the cam 22 rotates on the shaft 21 or may be held either in raised or lowered position to permit one or the other of the shuttles to remain active a considerable number of picks 15 irrespective of the movements of the cam 22. Accordingly, in carrying my invention into effect I provide a fixed stud 30 mounted on a bracket 31 secured to the loomside and mount on said stud 30 a pair of disks shown 20 herein as of unequal sizes for the sake of clearness. The smaller disk 32 has secured thereto the upper end of a cord, strap or other flexible connection 33, the lower end of which extends around a sheave 34 and is 25 connected to the cam lever 26 as at 35. A tension spring 36 interposed between a pin 37 on the bracket 31 and a portion of the disk 32 as at 38 tends normally to turn the disk 32 in a counterclockwise direction, thus holding the lever 26 against the cam 22. As 30 the cam shaft rotates during the normal operation of the loom the disk 32 will oscillate back and forth about the stud 30, being moved to the right positively by the cam and 35 cam lever and being moved to the left on the return stroke by the spring 36.

The previously mentioned flexible connection 18 by means of which the boxes are raised and lowered extends around and 40 under sheave 20, around a second sheave 40, and then upwardly to be secured as at 41 to the second and larger disk 42. By means of the connection between the boxes and said disk 42 right hand movement of the latter will raise the boxes, said boxes falling 45 of their own weight when the disk 42 is free to rock in the opposite direction.

The devices for normally causing the disks to rotate together include a bar 43 slidably 50 mounted on the disk 32 and having pivotal connection with an armature lever 44 pivoted to the disk 32. The right hand end of the slide 43 as viewed in Fig. 1 will normally be held projected beyond the periphery of the disk 32 by a light tension spring 55 interposed between the armature lever and a part of the disk 32. When in this position the end of the slide bar 43 will lie in the path of a lug 46 projecting laterally 60 from the disk 42. With the parts in this position the slide 43 will engage the lug 46 as the disk 32 moves in a right hand direction under the influence of the cam 22 to cause the larger disk 42 also to have a right 65 hand movement, thus pulling on the flexible

connection 18 to lift the boxes 13. When the cam lever 26 moves in the opposite direction the spring 36 together with the weight of the boxes will cause the disks to have a left hand movement. The boxes rise 70 and fall with the rotation of the cam 22, but it will be understood that I do not wish to be limited to the particular movement of the cam or boxes, although as shown herein one shuttle will be active for two picks and 75 will then move out of action while the other shuttle is active for two picks to give a two and two box change.

My invention further relates to the means for disconnecting the disks 32 and 42 and holding the latter in locked position so that the constant vibration of the lever 26 need not be communicated to the shuttle boxes when it is desired to repeat any one color for a large number of picks. This feature 80 of my invention is carried out by providing disk 42 with two notches 50 and 51, respectively, which as shown in Fig. 1 are proportioned to receive the lower end of a lock lever 52 pivoted to the bracket 31. Said 85 lock lever is normally held raised in inoperative position by a light tension spring 53. In order to disconnect the disk 32 from the disk 42 I mount on the former an electromagnet 60 which is positioned to attract the 90 depending arm 61 of the armature lever 44 when said magnet is energized and withdraw the slide bar 43 out of position with 95 respect to the lug 46.

The mechanism for controlling the electromagnet 60 and lock lever 52 is illustrated at the right hand side of Fig. 1, where it will be seen that the frame 62 preferably of insulating material is secured on the loomside and has vertically mounted therein for rotation a screw 63 which extends through and has threaded connection with a travelling contact member 64 having right and left hand contact spring arms 65 and 66, respectively, see Fig. 6. The arms 65 and 66 are 100 arranged for engagement electrically with contact strips 70^a, 70^b and contact points 71^a, 71^b mounted on the frame 62 and the screw 63 may be electrically connected to electric contact plate 47 carried by but insulated from 105 lever 26 by means of wire 72.

The mechanism for rotating the screw 63 includes an arm 75 secured to the rocker pin 17 and extending upwardly so as to pivotally support upper and lower pawls 76 and 110 77, respectively. As shown in Figs. 4 and 5 each of said pawls is provided with a hold spring 78 which lies between a pin 79 fixed to the arm 75 and a pin 80 secured to the pawl. The spring is so located that as the 115 pawls move from one position to another the spring will pass over the center of the pawl to complete the movement of the latter. Each pawl is provided with a pair of stop screws indicated at 81 which engage a por- 120

tion of the arm 75 to limit movement of said pawls under action of the springs.

Said pawls cooperate with a pair of ratchets, one indicated at 82 being for the upper pawl 76 and the other indicated at 83 being for the lower pawl 77. Said ratchets are both secured to a stud shaft 84 mounted in fixed bearings 85, and said shaft has secured thereto a bevel pinion 86 which meshes 10 with another bevel pinion 87 secured to a shaft 88, see Fig. 5. Bevel pinion 89 secured to the shaft 88 meshes with a similar pinion 90 secured to the lower end of screw 63. Said screw may have a shoulder 91 15 as shown in Fig. 4 to limit downward movement of the screw and afford a support therefor.

A weighted rocker arm 92 pivoted relatively to the support 62 adjacent the upper 20 end of the screw is positioned for mechanical engagement with spring arm 66 carried by the member 64, said spring arm tending to lift the rocker arm 92 away from stop 48 as the member 64 moves to the upper limit 25 of its movement. A second weighted rocker arm 93 pivoted to the bracket 62 is positioned for engagement by said contact arm 66 as the latter nears the lower limit of its movement to depress said arm 93. An extension 94 on the rocker arm 93 is connected 30 by means of a flexible cord 95 extending around sheave 96 to the lower pawl 77 and the rocker arm 92 is connected by a flexible cord 97 to the upper pawl 76, said pawls being connected together by a link 98 causing them to move vertically in unison.

As the lay moves back and forth arm 75 will carry one or the other of the pawls into engagement with the corresponding ratchet 40 wheel and the stud shaft 84 will be given an angular movement in one direction or the other to cause a corresponding movement on the part of the vertical screw 63. When the parts are in the position shown in Fig. 1 and the contact member is at the bottom of its travel so that lever 93 is depressed to throw pawl 77 out of action and pawl 76 into action, continued running of the loom will cause a rotation of the right hand threaded 50 screw 63 in the direction of arrow A so that the contact member 64 will begin to rise. The boxes 13 will be controlled by the cam 22 until the contact member engages one of the contact strips. As soon as arm 66 55 contacts with the strip 70^a the following circuit will be closed; current will flow from battery B along wire 100, wire 101, electro-magnet 102, switch 103, wires 104 and 105, contact strip 70^a, contact arm 66, contact 60 member 64, screw 63, wire 72, contact plate 47 on lever 26, contact 107, wire 106 back to the battery B. When this circuit is closed electro-magnet 102 will be energized to move the lock lever 52 downwardly so that the 65 locking end thereof will enter one or the

other of the locking pockets 50 or 51. As shown herein the pocket 50 is properly positioned to receive the locking lever 52 and it will further be seen that the circuit just traced will not be completed until the lever 70 26 is in the position shown in Fig. 1 to establish connection between contact plate 47 and contact 107 and that such contact takes place only at such times as pocket 50 is in position to receive the lever 52. The 75 disk 42 is now locked against movement so that the boxes 13 will remain down.

In order to prevent the next movement of disk 32 from tending to rock disk 42 it is necessary to withdraw the slide bar 43 and this is done by closing a circuit including contact plate 108 carried by but insulated from the lock lever 52. When the lock lever is depressed a second circuit will be closed as follows; battery B, wire 100, wire 110, 80 electro-magnet 60, wire 111, contact point 109, contact plate 108, wire 112, wire 106 back to the opposite pole of the battery. The effect of closing this second circuit is to energize electro-magnet 60 which, when energized, will attract the arm 61 of the armature lever 44 against the action of light spring 45 to move the protruding end of the sliding bar 43 inwardly out of the path of the lug 46 on disk 42. This circuit will be 90 closed as long as the lock lever 52 holds the disk 42 against angular motion and the disk 32 may oscillate on its pivot under the influence of cam 22 without imparting its motion to the disk 42. In this way connection 100 between the disks is interrupted at the time disk 42 is held in locked position and the weight of the boxes being supported by the lock lever 52 and notch 50 tends to preserve mechanical contact between the lever 52 and disk 42 to overpower the action of light tension spring 53. The periodic interruptions to the first circuit traced due to the oscillation of lever 26 toward and from contact 105 107 will therefore not act to release the disk 110 42 when the electro-magnet 102 is deenergized.

As the screw 63 continues to rotate the contact member will ascend and in time spring contact arm 66 will leave contact 115 strip 70^a and electro-magnet 102 will be deenergized, but as previously explained the lock lever 52 will be held down by the weight of the boxes. In fact, the contact strip 70^a may be replaced by a contact point 120 if desired. As the contact member 64 moves upwardly contact finger 66 will engage point 71^a and a third circuit will be closed as follows; battery B, wire 100, wire 101, wire 113, electro-magnet 114, wire 115, switch 125 116, wire 117, contact point 71^a, contact finger 66, contact member 64, screw 63, wire 72, contact plate 47, contact 107, wire 106, back to the opposite pole of the battery. Current flowing in this third circuit will en- 130

ergize electro-magnet 114 the effect of which will be to raise lock lever 52 and release disk 42. A further effect of closing this third circuit is to break the contact between points 5 108 and 109 so that the second circuit including electro-magnet 60 is broken and spring 45 will act to move the sliding bar 43 into the path of the lug 46. Thus it will be seen that by closing this third circuit disk 10 42 is unlocked and slide 43 is rendered operative to cause movement of disk 32 to be transmitted to the disk 42. The light spring 53 serves to hold the lock lever 52 elevated even though electro-magnet 114 be deenergized as soon as lever 26 moves away from contact point 107 to interrupt the third circuit. Inasmuch as spring 53 is sufficiently strong to break the circuit between the contacts 108 and 109 the contact 71^a may be 20 merely a point.

As the contact member 64 nears the upper limit of its travel the contact finger 66 will engage the rocking lever 92 to raise the same to cause an upward pull on the cord 97 the effect of which will be to lift pawl 76 out of position with respect to its ratchet and to lift pawl 77 into action relatively to pawl 83, these pawls being held in position by the springs 78 as shown in Figs. 4 and 5. 30 A continued movement of the loom therefore effects a reversal of the screw 63 and the contact member will begin to descend. Only half of the repeat has been completed however when the contact member reaches the upper limit of its movement and the contact strips and points 70^b and 71^b respectively, lying to the right of the screw 63 as shown in Fig. 1 are depended upon for completing the pattern. The switches 103 35 and 116 were raised while the contact member was going up and for this reason the contact strips and points 70^b and 71^b on the right hand side of screw 63 were disconnected circuits so that although they had electrical contact with finger 65 yet they exerted no control over the mechanism. The upward pull of the cord 97, however, causes a throwing of the switch 103 by the mechanism shown in Fig. 7. As shown 40 therein the cord has operative connection with a link 118 insulated from but connected to switches 103 and 116 to cause them to move in unison and said cord is trained around a set of sheaves as shown in Fig. 55 7. As the rock lever 92 moves to reverse the direction of the screw 63 the cord 97 will also act to lower link 118 to throw switches 103 and 116 to low position. Switch 103 will then be electrically connected by wire 119 to contact strips 70^b on the right of screw 63 and switch 116 will be connected by wire 120 to contact points 71^b. At the same time contact strips and points 70^a and 71^a will be disconnected so 60 65 that they can exert no influence of the pre-

viously traced circuits. As the contact member moves downwardly the first and third circuits already traced will be closed through contact strips and points 70^b and 71^b, instead of through members 70^a and 71^a. 70 When the contact member 64 reaches its low position the pattern repeat will be completed and the rock lever 94 depressed to restore the parts to the position shown in Fig. 1, after which the sequence of operations described will be repeated. 75

The repeat will not always be of the same length and to provide for this condition I mount the rocker arm 92 on a small block 130 and secure the same to the support 62 80 by means of bolt 131 which extends through a slot 132 lying vertically in the support 62. A stop 48 for the lever 92 is also carried by the block 130 and when the latter is moved to assume a new position a corresponding change will be made in the length of the cord 97. In this way the length of travel of the contact member 64 may be varied to meet the changing conditions of the repeat. The contact strips and points are 85 arranged in such order as to determine the times when the cam 22 shall control the boxes and when certain boxes shall remain at rest to keep one shuttle active, contact of one of the contact spring arms 65 or 66 with the contact strip causing a multiplying action to disconnect the disks and contact of said spring arms with one of the points 71^a or 71^b restoring the boxes to control the cam 22. 90 95 100

The description given hereinbefore was in connection with pocket 50 and contact 107, but it is to be understood that the contact strips and points can be so placed as to energize electro-magnet 102 when the pocket 105 51 is under the lock lever 52 and the contact strip 47 touches contact 140. The latter is connected to the battery B by wire 141 and the previously traced circuits involving contact 107 can be completed by means of wire 110 141 and contact 140 when the lever 26 is moved to such a position as would raise the boxes and place pocket 51 under the lock lever 52. 110

From the foregoing it will be seen that I 115 have provided an electrical control for a box motion wherein the periodic movement of the disk 42 may be interrupted for any desired length of time to hold the boxes at rest. It will further be seen that the up 120 and down movement of the contact member 64 completes the pattern thereby permitting double the length of a comparatively long screw to correspond with the repeat in the pattern. Also, the disks are connected and disconnected in predetermined order and operate to transmit the motion of the cam 22 to the boxes or to hold the latter out of control of said cam. 125

Having thus described my invention it 130

will be apparent that changes and modifications may be made therein by those skilled in the art without departing from the spirit and scope of the invention, and I do not 5 wish to be limited to the details herein disclosed but what I claim is:

1. In a loom having a periodically moving part requiring a plurality of picks of the loom to complete its cycle and shifting 10 shuttle boxes, a lay, a regularly moving device to shift said shuttle boxes relatively to the lay in predetermined sequence, and electro-magnetically operated means including a progressively movable contact member operatively related to the periodically moving part to disconnect said regularly moving device from the shuttle boxes.

2. In a loom having a periodically moving part and shifting shuttle boxes, a regularly moving device to impart shifting movement to the boxes, and electro-magnetically controlled means including a travelling contact member actuated by the periodically moving part to disconnect said 25 device from the boxes.

3. In a loom having a periodically moving part requiring a plurality of picks of the loom to complete its cycle and shifting shuttle boxes, a lay, means to move said boxes 30 relatively to the lay in a predetermined order, and electro-magnetically operated means including a contact member moving in timed relation with a moving part of the loom to disconnect the shuttle boxes from 35 the member at predetermined intervals.

4. In a loom having a periodically moving part requiring a plurality of picks of the loom to complete its cycle and shifting shuttle boxes, a lay, mechanism to give said 40 shuttle boxes shifting movements relatively to the lay in a predetermined order, a travelling contact member, connections between the periodically moving part and said contact member to give the latter a regular 45 movement as the loom operates, and electro-magnetic means electrically connected to the contact member to disconnect the mechanism from the boxes at predetermined intervals during the travel of the contact member.

5. In a loom having a lay and shifting shuttle boxes, movable in opposite directions along a line fixed relatively to the lay mechanism to give said boxes shifting movements in predetermined order, and electro-magnetic means including a contact member having a regular movement while the loom is running to render said electro-magnetic means effective to disconnect the mechanism from the shuttle boxes at predetermined 55 intervals.

6. In a loom having a lay and shifting shuttle boxes, movable in opposite directions along a line fixed relatively to the lay actuating mechanism to shift the boxes in a predetermined order, electro-magnetic means 65

to disconnect said actuating mechanism from the shuttle boxes at predetermined intervals, said electro-magnetic means including contact points on a contact member, and means to cause relative movement between the contact points and the contact member as the loom runs. 70

7. In a loom having shifting shuttle boxes, actuating mechanism to move said boxes in predetermined order, a contact member to receive a progressive movement as the loom runs, electro-magnetic means to disconnect the actuating means from the boxes, and additional electro-magnetic means to lock the boxes when disconnected from the actuating 80 mechanism, both of the electro-magnetic mechanisms being controlled by the contact member. 75

8. In a loom having shifting shuttle boxes, actuating mechanism to give the boxes shifting movements in a predetermined order, electro-magnetic means to lock the boxes against movement, and additional electro-magnetic means brought into action by the first named electro-magnetic means to disconnect 90 the actuating mechanism from the shuttle boxes. 85

9. In a loom having shifting shuttle boxes, actuating mechanism to shift the shuttle boxes in a predetermined order, electro-magnetic means to lock said boxes against movement, a second electro-magnetic means brought into action by the first named electro-magnetic means to disconnect the actuating mechanism from the boxes and a third 95 electro-magnetic means to unlock the boxes and to disable the second named electro-magnetic means to establish operative connection between the actuating mechanism and the shuttle boxes. 100

10. In a loom having a lay and shifting shuttle boxes, movable in opposite directions along a line fixed relatively to the lay actuating mechanism to shift the shuttle boxes in a predetermined order and including a moving member to assume two different positions, and electro-magnetic means effective only at such times as the moving member is in one or the other of said positions to disconnect the actuating mechanism from 110 the shuttle boxes. 105

11. In a loom having shifting shuttle boxes, actuating mechanism to shift the shuttle boxes in a predetermined order, and including a member moving between limits, 120 electro-magnetic means to lock the shuttle boxes against movement at such times only as said member is in one of its limiting positions, and additional electro-magnetic means to disconnect said actuating mechanism from the shuttle boxes when said first named electro-magnetic means locks the shuttle boxes. 125

12. In a loom having a lay and shifting shuttle boxes, movable in opposite directions along a line fixed relatively to the lay mecha- 130

nism to shift the shuttle boxes in a predetermined sequence, electro-magnetic means to disconnect said mechanism from the boxes, said means including a travelling contact member, means having a regular movement while the loom operates to give said contact member a progressive movement, and contact points electrically connected to the electro-magnetic means to be engaged in predetermined order by the contact member and effective when so engaged to cause said electro-magnetic means to disconnect the boxes and mechanism.

13. In a loom having shifting shuttle boxes, actuating mechanism normally connected to the shuttle boxes to shift the latter in a predetermined order, electro-magnetic means to disconnect the actuating mechanism from the shifting shuttle boxes, additional electro-magnetic means to reestablish connection between the actuating mechanism and the shuttle boxes, a set of contact members for each electro-magnetic means and a travelling contact member electrically connected to said electro-magnetic mechanisms and having a regular progressive movement as the loom operates to have alternate contact first with a contact member of one group and then with a contact member of the other group in predetermined order and at selected intervals to interrupt and reestablish connection between the actuating mechanism and the shuttle boxes.

14. In a loom having a lay and shifting shuttle boxes, movable in opposite directions along a line fixed relatively to the lay actuating mechanism normally connected to the shuttle boxes to cause shifting of the latter in predetermined order, a plurality of spaced contact points, electro-magnetic means to prevent shifting of the boxes electrically connected to said contact points, a travelling contact member to have electrical contact at spaced intervals with said contact points, means establishing an electrical circuit including said contact member and one of the contact points and said electro-magnetic means when said contact member engages any one of the contact points to energize said electro-magnetic means to prevent shifting of the boxes.

15. In a loom having shifting shuttle boxes, actuating mechanism normally connected to the shuttle boxes to cause shifting of the latter in predetermined order, a contact member movable in opposite directions in a fixed path, two spaced groups of contact points, electro-magnetic means to prevent shifting of the boxes, and means to electrically connect one group of contact points with the electro-magnetic means when said contact member is moved in one direction and to connect the other group of contact points with said electro-magnetic means when the contact member is moved in the opposite direction.

16. In a loom having shifting shuttle boxes, actuating mechanism normally connected to the shuttle boxes to cause shifting of the latter in predetermined order, a contact member, means to move said contact member in opposite directions along a fixed path, reversing mechanism for said means, electro-magnetic mechanism to prevent shifting of the boxes, two spaced groups of contact points to be engaged by the contact member, the groups to be electrically connected to the electro-magnetic means one at a time, and means to simultaneously reverse the direction of movement of the contact member and also electrically disconnect one group of contact points from the electro-magnetic means and electrically connect the other group thereto.

17. In a box motion for looms having a lay, regularly moving actuating mechanism, shifting shuttle boxes, a pair of co-axial independently movable rotatable members supported independently of the lay one of which is connected with the actuating mechanism and the other of which is connected to the shuttle boxes, means to cause said rotatable members to move together to cause the actuating mechanism to shift the boxes, and means to disconnect said rotatable members from each other, whereby the member connected to the actuating mechanism may move independently of the other member which is connected to the shifting boxes.

In testimony whereof I have hereunto affixed my signature.

JOSEPH N. DUMAS.
